K. 2958

Design for Plates of a Hop-Stove.

By Nicholas S. Vedder, of Troy, N.Y.
Assignor to George Williamson & Co., of Milwaukee, Wis.

United States Patent Office.

NICHOLAS S. VEDDER, OF TROY, NEW YORK, ASSIGNOR TO GEORGE WILIAMSON AND COMPANY, OF MILWAUKEE, WISCONSIN.

Design No. 2,958, dated March 17, 1868.

DESIGN FOR THE PLATES OF A HOP-STOVE.

The Schedule referred to in these Letters Patent and making part of the same.

TO ALL WHOM IT MAY CONCERN:

Be it known that I, NICHOLAS S. VEDDER, of the city of Troy, in the county of Rensselaer, and State of New York, have invented or produced a new and original ornamental Design for Plates of a "Hop-Stove," of which the following is a full and exact description, reference being had to the accompanying photograph of the greater portion of a hop-stove having my said design.

In this invention or production, the ornamental design of the upright plates of the stove consists of the central ornament *a* and surrounding moulding *b*, arranged together upon the smooth-surface panels *c*, as most clearly represented on the side plates *D* of the stove; and the design of the top plate *E* consists of the edge-moulding *f*, ledge-moulding *g*, and interior-moulding *h*, surrounding the plane surface *i*, as shown in the aforesaid photograph.

What I claim as my invention or production, and desire to secure by Letters Patent, is—
The design for plates of a hop-stove herein set forth and shown.

In testimony whereof, I hereunto set my hand, this 23d day of January, 1868.

NICHOLAS S. VEDDER.

Witnesses:

AUSTIN F. PARK,
LESLIE SMYTH.
